EDGE FINISHING LEATHER ARTICLES

Hiotte A. Davis, Lynchburg, Va., assignor to
United Shoe Machinery Corporation, Borough
of Flemington, N. J., a corporation of New
Jersey

Application November 12, 1938, Serial No. 240,062

4 Claims. (Cl. 12—146)

This invention relates to edge finishing of sheet leather articles and is illustrated herein by way of example but not of limitation as embodied in a shoe upper.

5 Where the upper of the shoe is lined no difficulty arises in effecting a suitable edge finish inasmuch as the margin of the leather may be folded and the raw edge concealed by the backing or lining. However, the edge finishing of unlined 10 shoe uppers presents certain difficulties which it is the principal object of this invention to overcome. More particularly, it is an object of the invention to provide in an unlined shoe or other unbacked article of sheet leather a smooth 15 and neatly finished edge comparable to the edge finish obtained in shoes having lined uppers. An additional object of the invention as applied to shoe uppers is to provide in an unlined upper, a margin along the top of the quarter which may be used, without marring the upper, to tack the 20 upper to the last so that when the upper is tensioned prior to lasting there will be no tendency for the edges of the upper to pull away from the last, thereby causing a distorted shoe.

25 A further object is to provide a simple and practical method whereby the foregoing objects are attained.

Briefly, the invention comprises a shoe or other article of sheet leather having its edge formed 30 in two integral parts defined by a split extending inwardly of the edge along the margin, the edge of the outer or grain surfaced portion being folded, the two parts being fastened together with some permanent securing means such as 35 cement or stitching, and the margin of the inner or flesh portion being trimmed along a line substantially flush with the fold of the outer portion. It may be found desirable for the article to have the edges of one or both of the split portions 40 skived or reduced in thickness to provide a finished edge substantially equal in thickness to the main body of the leather sheet.

In the drawing,

45 Fig. 1 is a perspective view of a shoe embodying the invention, a portion being broken away to disclose the construction of the edge of the upper in cross section;

Fig. 2 is a cross section on a larger scale of the 50 edge of the upper after the splitting operation;

Fig. 3 is a similar view showing the edge after cementing and folding the outer or grain side;

Fig. 4 is another cross sectional view illustrating the edge after stitching and trimming; and

55 Fig. 5 is a view similar to Fig. 4 showing a

modification in which the margins of the respective split portions are skived.

As illustrated, an upper U is split along its top margin inwardly of the edge to define two portions, an outer split part 22 and an inner split 5 part 24. A margin 26 of the outer or grain side portion 22 is folded inwardly on itself toward the line along which the upper U is split, and secured there by a band of adhesive such as rubber cement 28. The inner or flesh side 10 portion 24 and the folded outer side portion 22 are bound together by cement 28 or by stitching 30, or partly by the cement 28 and partly by the stitching 30, which extends through the flesh side split 24, the inwardly folded margin 26 of 15 the grain split portion and the main body 22 of the grain split portion.

To produce the invention, applicant has devised a simple and inexpensive method the several steps of which are illustrated in Figs. 2 to 5. As shown 20 in Fig. 2, the top margin of an upper U is first split inwardly from the raw edge along a plane approximately parallel to the surface of the leather and the split opened, thus forming two 25 portions or flaps, the one 22 having for its outer surface the finished or grain side of the leather and the other 24 having the flesh side for its outer surface. This split may, of course, be made at any point in the thickness of the leather. An 30 adhesive 28, preferably rubber cement, is then applied to the inner surface of the flaps 22 and 24. The grain flap 22 is then folded inwardly upon itself and the infolded margin 26 secured in position by the adhesive 28. Preferably, the 35 split dividing the flaps has been located as close to the grain surface as is practicable since the thinner the grain portion can be made the less additional thickness there will be in the edge of the finished article.

After folding, the split between the two portions 40 is closed by bringing them together, in which position they are adhesively held by the cement 28. The two portions may then be permanently fastened together by the stitches 30 (Fig. 4) and the projecting margin 32 of the flesh portion 24 45 trimmed along a line substantially flush with the fold in the outer portion. Obviously the trimming operation may be done before or during stitching, or if the margin 32 of the flesh portion 24 is to be tacked to the last to hold the top line 50 of the upper in place during the pulling over operation on the shoe, the trimming may be deferred until after the shoe has been lasted.

Alternatively, the stitching may be omitted and the two portions bound together by means of 55

cement alone. In such case the finished surface of the inturned margin 26 would usually be roughened to permit the cement to penetrate the leather and make a firm bond. Furthermore, in making articles other than shoes, or in shoemaking where the margin 32 of the flesh split 24 is not to be used for tacking the upper to the last, it may be found desirable to trim off the surplus margin 32 of the flesh portion 24 prior to cementing, since the inner surface of that part of the flesh side which is not trimmed away will preferably be cemented throughout its entire width, and by thus trimming, any danger of smearing the folded edge of the grain side with cement when the two portions are brought together is eliminated.

It may be found desirable after the splitting operation, and before cementing and folding, to skive or otherwise reduce in thickness the margin of one or both portions of the leather at 23 and 25, as shown in Fig. 5. This would preferably be done on the inner surface of the flaps 22 and 24. By adding this step the edge may be finished with substantially no increase in thickness over the main body of the leather sheet after completion of the operation.

It will be evident to anyone skilled in the art that the order of performance of the operations may be varied considerably without departing from the scope and fundamental spirit of the invention.

From the foregoing it will be apparent that the edges of an unlined shoe upper or other unbacked sheet leather article may be given a neat, attractive appearance and the finished product will have an edge resembling that of an article having a lining or backing. If desired, the flesh side of the leather may be treated by roughing or otherwise to simulate suede or other suitable lining material as shown at 34, in Fig. 1.

Having thus described my invention, what I claim as new and desire to secure by Letters Patent of the United States is:

1. An article of sheet leather comprising two integral marginal portions defined by a split extending inwardly from the edge, the grain por-

tion being folded inwardly upon and against itself, and the flesh portion being trimmed along a line substantially flush with the outer surface of the fold in the grain portion, thereby to simulate a lining, and means permanently securing the folded grain portion to the inner side of said flesh portion.

2. An article of sheet leather comprising two integral marginal portions defined by a split substantially parallel to the surface of the leather, at least one of said portions being reduced in thickness, the grain portion being folded inwardly upon and against itself and the flesh portion being trimmed along a line substantially flush with the outer surface of the fold in the grain portion, thereby to simulate a lining, and means permanently securing the edge of the folded grain portion to the split surface of said flesh portion.

3. That improvement in methods of finishing the top edges of unlined leather shoe uppers which comprises splitting the top edge of the leather inwardly of said edge, folding the margin of the outer split portion inwardly upon and against itself, thereby leaving the inner split portion projecting for tacking to a last, securing the folded outer split portion to the inner portion, and thereafter trimming the inner portion substantially flush with the outer surface of the fold of the outer portion.

4. That improvement in methods of finishing the top edges of unlined leather shoe uppers which comprises splitting the margin of the leather along a plane approximately parallel to the surface of the leather, reducing the marginal thickness of at least one of the split portions, folding the margin of the grain split portion inwardly upon itself thereby leaving the flesh split portion projecting for tacking to a last, permanently securing two split portions together, and subsequently trimming the flesh portion substantially flush with the outer surface of the fold in the grain portion.
